UNITED STATES PATENT OFFICE.

CHARLES S. FINNEY, OF ST. PAUL, MINNESOTA, ASSIGNOR TO KOEHLER & HINRICH'S CO., OF ST. PAUL, MINNESOTA, A CORPORATION OF SOUTH DAKOTA.

DESIGN FOR A BILLIARD-TABLE.

49,179.

Specification for Design. Patented June 13, 1916.

Application filed April 15, 1916. Serial No. 91,440. Term of patent 7 years.

To all whom it may concern:

Be it known that I, CHARLES S. FINNEY, a citizen of the United States, residing in the city of St. Paul, county of Ramsey, and State of Minnesota, have invented a new, original, and ornamental Design for Billiard-Tables, of which the following is a specification, reference being had to the accompanying drawing, forming part thereof.

The figure is a perspective view of a billiard table, showing my new design.

I claim:

The ornamental design for a billiard table, as shown.

CHARLES S. FINNEY.
